DESIGN FOR A PLATE OR SIMILAR ARTICLE.

Application filed August 3, 1928. Serial No. 27,687. Term of patent 7 years.

To all whom it may concern:

Be it known that I, HEINRICH RAMPFEL, a citizen of the United States, residing at 105^B Chestnut Street, Lakewood, in the county of Ocean and State of New Jersey, have invented a new, original, and ornamental Design for Plate or Similar Article, of which the following is a specification, reference being had to the accompanying drawing, forming part thereof.

The figure is a plan view of a plate or similar article showing my new design.

The design being a repetition of a unitary design, a segment only of the complete design is illustrated in the drawing; it being understood that the unit included in the drawing is merely repeated to form the entire design.

I claim:

The ornamental design for a plate or similar article substantially as shown and described.
